WALL CONSTRUCTION

Filed Dec. 12, 1930

UNITED STATES PATENT OFFICE

JOSEPH L. LEMEROND, OF GREEN BAY, WISCONSIN

WALL CONSTRUCTION

Application filed December 12, 1930. Serial No. 501,843.

This invention relates to improvements in wall construction.

One of the objects of the present invention is the provision of an improved type of wall construction wherein separable blocks of tile, brick, or similar materials are used for building up the wall, and the invention resides in improved means for retaining these blocks in position without the use of mortar or other similar materials.

Another object of the present invention is the provision of an improved wall construction built up of a plurality of superposed blocks, each having spaced parallel grooves extending through both side faces and through both ends, whereby locking strips are arranged within the grooves on the side faces upon opposite sides of the blocks and are connected by means of cross strips arranged in the grooves in the ends of the blocks, thus retaining the blocks against movement relative to each other when laid in superposed relation.

Another object of the invention is the provision of an improved wall construction of the above character wherein means is provided for locking the wall to a second wall, so that the improved wall construction can be used as a facing, if desired.

A still further object of the invention is the provision of an improved wall construction, including means for locking two adjacent walls of similar character so that a double wall can be readily formed, and the two walls securely locked against movement relative to each other.

With the above and other objects in view, the invention consists in the novel features of construction, the combination and arrangements of parts hereinafter more fully set forth, pointed out in the claims and shown in the accompanying drawing wherein:

Figure 1 is a top plan view illustrating a wall constructed in accordance with my invention;

Figure 2 is a side elevation of a portion of a wall with parts thereof broken away and illustrated in cross section;

Figure 3 is a detailed section on the line 3-3 of Figure 2;

Figure 4 is a detailed perspective view of one of the cross connecting members;

Figure 5 is a detailed section illustrating the manner in which the wall can be locked to a second wall; when used as a facing; 55

Figure 6 is a detailed perspective view of one of the locking members used in connection with the construction shown in Figure 5;

Figure 7 is a detailed section of two adjacent walls showing the manner in which they can be locked together; 60

Figure 8 is a detailed perspective view of one of the locking members for two adjacent walls, such as illustrated in Figure 7; and, 65

Figure 9 is a plan view of one of the blocks.

In constructing a wall of the character set forth, I provide a plurality of similar blocks and these blocks are built up into wall form by arranging them in superposed relation, 70 as shown in Figure 2, the building up of the wall being somewhat in the manner of the building of a brick or tile wall, where mortar or other similar material is used. However, the blocks 1 used in this construction as illustrated in Figure 9 are each provided with spaced parallel grooves 2, extending through both top and bottom faces and with additional grooves 3 extending through both ends. 75

As shown in Figure 1, longitudinal strips 4 are arranged in the parallel grooves 2 and may be of sufficient length to extend throughout the length of the wall. Ordinarily, these strips 4 are somewhat narrower than the grooves 2 and considerable space is left upon 80 both sides of a strip in each groove, this space being filled with any suitable type of material, such as mortar or the like, to securely retain these strips in position.

The blocks used at the corners of the wall, 85 as shown in Figure 1 have one end of the grooves 2 extended at right angles in order to lead into the longitudinal grooves of an adjacent wall section, and if the strips 4 are long enough, they can be bent at right angles, 90 as shown at 5 and extended on through an adjacent wall section. This operation may be continued throughout the four walls of a building.

It will be noted in Figure 2, that the strips 100

4 are arranged upon opposite sides of the blocks with a portion of each strip arranged in each layer of blocks. In other words, the strip in the lowermost layer has a portion thereof extending into the bottom groove of the uppermost layer, and the parallel superposed strips arranged upon opposite sides of the blocks of each layer are connected by means of the U-shaped straps 6, the intermediate portion of which will embrace the lowermost strip, while the upper ends thereof are cutaway to form overlapping tongues 7 which engage over the upper strips, of each layer, as shown in Figures 2 and 3. These connecting members 6 are so arranged with respect to each layer of blocks that the superposed strips are all connected together through the alternate arrangement of the connecting members, as illustrated in Figure 3.

Should it be desired to use this type of wall construction as a facing for a standing wall, I provide connecting members, one of which is illustrated in perspective in Figure 6. These connecting members are each provided with a hook portion 8 at one end thereof and with a horizontal portion 9, the hook portion engaging over one of the longitudinal strips 4, as shown in Figure 5, while the horizontal portion rests upon one of the blocks. The end of the connecting member opposite the hook portion 8 is provided with an apertured tab 10 adapted to receive through the aperture thereof a fastening element, such as a nail or the like, as shown at 11, said fastening element being engaged with the standing wall, a portion of which is illustrated at 12. These fastening elements may be arranged between each layer of blocks and connected with the standing wall.

In Figures 7 and 8, I have illustrated means for connecting two adjacent walls, whereby these adjacent walls will be securely retained against movement relative to each other. The connecting members are provided with a substantially flat body portion 13 adapted to be disposed between superposed layers of blocks and to be engaged by the opposed faces of the layers as shown in Figure 7, while at each end of the body, hook members 14 are provided and adapted to be engaged over one of the connecting strips 4 in each wall, thus securely retaining the walls against lateral movement relative to each other.

From the foregoing description, it will be readily apparent that I have provided an improved wall construction wherein superposed layers of blocks are securely held against lateral movement and the use of mortar or other similar material is dispensed with for connecting the blocks one to the other. By positioning the strips 4 upon opposite sides of each layer of blocks and then connecting opposed layers of strips

with the members 6, with the members 6 arranged in alternate relation, as illustrated, the blocks 1 will be securely held in position to form a wall, and the wall can be quickly built up through the medium of the strips 4 and the connecting members 6.

While I have shown and described the preferred embodiment of my invention, it will be apparent from the foregoing that slight changes may be made in the construction when putting the invention into practice without departing from the spirit of the same or the scope of the appended claims.

I claim:

1. In a wall construction, a plurality of superposed blocks, each of said blocks having a longitudinal groove encircling its top, bottom and end faces, longitudinal strips positioned in the groove of the top and bottom faces, and clips positioned in the grooves of the end faces for connecting the adjacent strips. 80

2. In a wall construction, a plurality of superposed blocks, each of said blocks having a longitudinal groove encircling its top, bottom and end faces, longitudinal strips positioned in the grooves of the top and bottom spaces, and bendable U-shaped clips having reduced, overlapping, folded ends positioned in the grooves of the end faces for connecting the adjacent strips. 90

3. In a wall construction, a plurality of superposed blocks, each of said blocks having a longitudinal groove encircling its top, bottom and end faces, longitudinal strips positioned in the grooves of the top and bottom faces, clips positioned in the grooves of the end faces for connecting the adjacent strips, and laterally extending anchor straps engaging said strips. 100

In testimony that I claim the foregoing I have hereunto set my hand at Green Bay, in the county of Brown and State of Wisconsin.

JOSEPH L. LEMEROND.
